[57] CLAIM

The ornamental design for a curved glass refrigerated merchandizer, as shown and described.

DESCRIPTION

FIG. 1 is a front elevational view of the curved glass merchandiser of the present invention;

FIG. 2 is a right side elevational view of the curved glass merchandiser of the present invention;

FIG. 3 is a back elevation view of the curved glass merchandiser of the present invention;

FIG. 4 is a left side elevation view of the curved glass merchandiser of the present invention;

FIG. 5 is a top plan view of the curved glass merchandiser of the present invention;

FIG. 6 is a bottom plan view of the curved glass merchandiser of the present invention; and,

FIG. 7 is an isometric view of the curved glass merchandiser of the present invention.

The dashed line representations of casters as shown in FIGS. 1,2,3,4,6, and 7 are for illustrative purposes only and do not form any part of the claimed design.
